UNITED STATES PATENT OFFICE.

CHARLES A. LINDSTRÖM, OF PITTSBURGH, PENNSYLVANIA, ASSIGNOR TO RATCHET BRAKE COMPANY, OF NEW YORK, N. Y., A CORPORATION OF DELAWARE.

BRAKE-ACTUATING MECHANISM.

1,120,151.

Specification of Letters Patent.

Patented Dec. 8, 1914.

Application filed June 21, 1912. Serial No. 704,992.

To all whom it may concern:

Be it known that I, CHARLES A. LINDSTRÖM, a citizen of the United States, residing in Pittsburgh, county of Allegheny, State of Pennsylvania, have invented certain new and useful Improvements in Brake-Actuating Mechanism, of which the following is a specification.

My invention has relation to brake actuating mechanism.

More specifically stated, it relates to hand brake actuating mechanism of the type which includes drop levers which are adapted to be raised from a depending more or less vertical position to a horizontal position when it is desired to actuate the mechanism for the purpose of applying the brakes.

One of the objects of my invention is to provide an improved construction of means for automatically actuating the clutch mechanism which is interposed between the said hand lever and the brake staff when the said lever is raised or lowered.

Another object of my invention is to provide means whereby such clutch mechanism may be rendered inoperative independently of the movement of the handle from a horizontal position to a dropped or depending position.

A still further object of my invention is to provide a structure comprising a drop hand lever associated with means for automatically controlling the clutch mechanism which is interposed between such lever and the brake staff for operatively connecting the said lever and the staff by the raising and the lowering of the said lever in combination with means independent of the said lever for disconnecting the said clutch mechanism from said staff.

Other objects and advantages of my invention will be specifically referred to hereinafter in the detailed description of my invention or will be apparent therefrom.

Certain forms of convenient embodiments of my invention are illustrated in the accompanying drawings, but it will be understood that changes in the details of construction may be made within the scope of the claims without departing therefrom.

In the drawings: Figure 1 is a horizontal section of a brake mechanism embodying my invention taken on the line 1-1 of Fig. 2, and also showing a top plan of the outer

end of the handle; Fig. 2 is a vertical section taken on the line 2-2 of Fig. 1, a portion of the handle being shown in side elevation and a portion thereof being shown as broken away; Fig. 3 is a transverse sectional view taken on the line 3-3 of Figs. 1 and 2; Fig. 4 is a view partly in elevation and partly in section, with parts broken away, of the upper end portion of a brake staff provided with brake actuating mechanism embodying my invention, the portion of the handle which is shown being in depending position; Fig. 5 is a perspective view of a pawl adapted to engage with and to be disengaged from a ratchet wheel secured upon the brake staff; Fig. 6 is a perspective view of a plunger adapted to act upon the said pawl to move it into engagement with the said ratchet wheel; Fig. 7 is a horizontal sectional view of a modified construction of mechanism embodying my invention, taken on the line 7-7 of Fig. 8; and also showing the top plan view of the handle portion of the same; Fig. 8 is a vertical section taken on the line 8-8 of Fig. 7 and also showing a portion of the handle in side elevation and a portion thereof being broken away; Fig. 9 is a transverse sectional view on the line 9-9 of Figs. 7 and 8; Fig. 10 is a view partly in elevation and partly in section, with parts broken away, of the upper end portion of a brake staff provided with my invention, of the said modified construction; Fig. 11 is a perspective view of a pawl having a stem integrally connected therewith which pawl is adapted to be engaged with and disengaged from the teeth of a ratchet wheel secured upon the brake staff; Fig. 12 is a vertical sectional view of my invention corresponding to the view shown in Fig. 2 and showing a manually operable lever for actuating the pawl illustrated in such Fig. 2, the upper end of the brake staff being shown in elevation and a portion of the handle being shown in side elevation and a portion being broken away; Fig. 13 is a vertical sectional view of my invention as the same is illustrated in Figs. 7 and 8 and showing in connection therewith in side elevation a manually operable lever for causing disengagement of the pawl from the teeth of the ratchet wheel, the upper end of the brake staff being shown in elevation and a portion of the handle being also shown in side elevation and a portion being broken away.

elevation and a portion thereof being broken away; Fig. 14 is a perspective view of the pawl shown in Fig. 13; Fig. 15 is a view in end elevation of a car having a brake staff 5 provided with brake actuating mechanism embodying my invention; Fig. 16 is a view in elevation of a portion of the side of a car illustrating the brake actuating mechanism comprising my invention and showing 10 the connection of the brake staff with the brake beam actuating rod underneath the car; and Fig. 17 is a view taken on the line 17—17 of Fig. 16 showing in plan a ratchet wheel secured to the said brake staff 15 and a pivoted pawl in engagement with the same.

Although my invention is illustrated in Figs. 15 and 16 of the drawings as being applied to a freight car of the gondola type, 20 it will be understood that it is as well applicable to cars of other constructions, such, for instance, as day passenger cars and Pullman passenger cars.

Referring to the drawings, 1 designates a 25 brake staff which is journaled at its upper end in a bearing 2 provided in a bracket 3 which is secured by means of bolts or otherwise to some portion of a car such, for instance, as the sides or ends of the body of 30 the car, being shown in Figs. 15 and 16 as connected with the end of the body of the car.

Referring now to Figs. 1 to 14, 16 and 17 of the drawings, the upper edge of the 35 bracket at points upon opposite sides of the bearing formed therein is provided with stop lugs 5 and 6 which are adapted to engage the opposite sides of a coöperating stop lug 7 formed upon a housing 10 which surrounds and is secured to the upper end portion of the brake staff 1. The lower end of the housing is reduced as indicated at 11 and the end of such reduced portion rests upon the upper edge of the bearing 2 as is 40 clearly shown in the drawings. 12 designates a ratchet wheel provided with a squared or angular opening which fits upon the squared or angular upper end portion 13 of the brake shaft 1. Such ratchet wheel 45 is located in the housing 10. The upper end of the housing is closed by means of a cap 14 having an upwardly projecting portion 15 which is hollow for the reception of the reduced upper end 16 of the brake staff 50 1. Such cap is secured to the reduced end 16 by means of a cross pin 17. The cap is also provided with an annular flange 18 which fits inside the upper end of the housing 10. The fit between the flange 18 and 55 the housing is such that the latter may be rotated relatively to the cap 14.

Referring now to Figs. 1 to 6 inclusive, the housing is provided with a hollow projection 20 which extends laterally from one 60 side thereof and is also provided with an

opening 21 in alinement with such projection in and through which opening a pawl 22, supported upon the housing structure, is adapted to operate for engagement with and disengagement from the teeth upon the ratchet wheel 12. The pawl is provided 70 with shoulders 23 for a purpose to be herein-after mentioned. 25 designates the handle by means of which the brake mechanism is actuated which handle at its inner end extends into the hollow projection 20 and is pivotally connected thereto by means of a pivot 26. The said handle is hollow and at the lower side of its inner end is provided with a cross web 27 upon which the lower edge of a flange 28 rests such flange being integral or otherwise connected to a plunger 30. The inner end of the said plunger is adapted to engage the outer end of the pawl 22. The outer end of the plunger 85 30 is supported in a bearing formed in a plate 31 extending across the opening in the handle 25. The said plunger is secured in its bearing in said plate by means of a pin 32. 33 designates a spring coiled around the plunger 30 with one end resting against the cross bearing plate 31 and the other end resting against the flange 28. The force of the said spring tends to cause inward movement of the said plunger, such force being 90 transmitted to the pawl 22 to cause the latter to engage the ratchet teeth upon the ratchet wheel 12. When the handle 25 is in the horizontal position indicated in Figs. 1 and 2 of the drawings, the said spring 100 operates to hold the pawl 22 in engagement with the ratchet wheel 12. The inner end of the handle 25, however, is provided adjacent to its lower edge at points beyond the pivot 26 with a couple of lugs 35 which 105 when the handle is dropped to a depending substantially vertical inoperative position as shown in Fig. 4 contact with the shoulders 23 upon the outer end of the pawl 22 and cause outward movement of the latter 110 to disengage the same from the said teeth. In order to permit angular movement of the upper edge or corner 36 of the inner end of the handle 25 the upper side of the projection 20 from the housing 10 is constructed 115 of arcuate shape, as clearly shown in Fig. 2 of the drawings, the center of said arcuate shaped portion being coincident with the axis of the pivot 26.

Referring now to Figs. 7 to 11 inclusive, 120 the handle 40 is secured to the projection 41 which extends from the housing 10 by means of a pivot 26. The bottom and opposite side portions of the inner end of the handle 40 extend into the projection 41, the 125 bottom being situated near the lower edge or side of the said housing while the opposite inner end portions of the sides are located inside of the opposite sides of the projection 41 in narrow spaces formed between 130

downwardly projecting ribs 42 and the inner surfaces of the opposite sides. The pivot pin 26 is connected to the inner end of the bottom of the said handle. The top 5 of the projection 41 is provided with raised or elevated portions 44 in which arcuate shaped spaces are provided concentric with the pivot 26 which spaces provide paths for the movement of the corners 45 at the inner 10 ends of the sides of the handle 40. Projecting inwardly from the lower edges of the inner ends of the sides of the handle, beyond the pivot 26, are lugs 46 which are adapted to engage shoulders 47 formed 15 upon the opposite sides of a pawl 48 when the handle is moved from the horizontal position shown in Figs. 7 and 8 to a depending substantially vertical position as shown in Fig. 10. The pawl projects 20 through and operates in the opening 21 formed in the side of the housing 10 in alinement with the central portion of the projection 41 and is supported upon the lower edge of the said opening and upon a 25 cross plate 49 extending between the inner end portions of the sides of the handle 40. The pawl 48 is also provided with an integral extension 52 which is slidably supported in an opening 53 in the outer closed 30 end 54 of the projection 41. A spring 55, which is coiled around the said extension 52 and one end of which bears against the outer closed end 54 of the projection 41 and the opposite end of which bears against 35 the flanges 56 formed upon the outer end of the pawl 48 exerts pressure against the said pawl to cause the same to move inwardly to engage the ratchet teeth upon the ratchet wheel 12.

40 When the handle is dropped from the position shown in Figs. 7 and 8 the lugs 46 thereon engage the shoulders 47 to cause the automatic outward movement of the pawl 48 in opposition to the spring 55 to disengage 45 the said pawl from the ratchet teeth on the ratchet wheel 12. On the other hand, a movement of the handle from the position shown in Fig. 10 to that shown in Figs. 7 and 8 removes the lugs 46 from contact 50 with the shoulder 47 and permits the spring 55 to cause automatic movement of the pawl inwardly to engage the said ratchet teeth.

Upon reference to the drawings, Figs. 1 55 to 11, it will be observed that when the handle is moved in one direction the beveled end of the pawls 22 and 48 ride over the teeth of the ratchet wheel 12, whereas when the handle is moved in the opposite direction, the said pawl engages the said ratchet teeth and causes rotation of the ratchet wheel together with the brake staff connected thereto. It will also be noted that the engagement of the lug 7 upon the housing 60 65 with the lugs 5 and 6 upon the bracket 2 lim-

its the angular movement of the said housing and the handle of the brake actuating mechanism. When the brake actuating mechanism is being operated for the purpose of applying the brake, it is necessary that means be provided for holding the brake staff against rotation during the interval when the handle is being returned to its initial position at which time the pawl or other equivalent device rides over the teeth of the ratchet device secured to the brake staff. For this purpose I have provided the usual ratchet wheel 60 which is secured to the lower end portion of the brake staff 1, as indicated in Fig. 16 of the drawings, which ratchet wheel is adapted to be engaged by a dog or pawl 61 pivoted to a stationary part of the car, which dog or pawl is adapted to be disengaged from the said ratchet by a kick of the foot or in any other convenient manner. The said ratchet and pawl also operate to hold the said staff against rotation during periods when the clutch mechanism (of whatever construction) for operatively connecting the handle to the staff is in disengaged or inoperative position.

The brake staff is extended in the construction illustrated to a point below the bottom of the car body, as indicated at 62, and to such extension the usual chain or other equivalent means 63 is secured which chain in this embodiment extends around a sheave 64 which is rotatably supported upon the end of a brake applying rod 65 underneath the car. From the said sheave the chain 63 extends toward the end of the car and is connected to a fixed point on the car as indicated at 66. When rotated in one direction the chain 63 is wound upon the extension of the brake staff 1 to apply the brakes through the brake applying rod 65 and when rotated in the opposite direction the said chain is unwound to release the brakes from the car wheels. At times, for instance, when it is desired to gradually release the brakes, it is desirable to have means to cause the disengagement of the pawls 22 and 48 from the teeth of the ratchet wheel 12 independently of any movement of the handles 25 and 40. To accomplish this end, I have provided the manually operable levers 70 which are pivoted at 71 and which are provided with handles 72 which are adapted to be grasped by the brakeman or operator for moving the said levers about their pivots and are also provided with extensions 73 which project through openings 74 in the projections 20 and 41 and extend into recesses 75 formed in the pawls 22 and 48. The lower ends of the projections 73 engage the outer walls of the said recesses 75 so that when the handle portion 72 of the said levers is depressed movement of the extension 73 is caused whereby outward movement of the pawl engaged thereby is 70 75 80 85 90 95 100 105 110 115 120 125 130

effected to cause its disengagement from the teeth of the ratchet wheel 12. It will, of course, be understood that the extension 73 of the lever 70 may be arranged so as to contact with any portion of a pawl for the purpose of causing this retraction when such lever is actuated in the proper direction. When it is desired to gradually release the brakes, the pawl is disengaged from the ratchet wheel by means of the manually operable lever 70, the brake staff after such disengagement being held against rotation by means of the pawl or dog 61 in engagement with the ratchet wheel 60 and the hand lever, the housing and the pawl connected therewith are moved angularly about the brake staff to such position as may be desired when the said lever 70 is released to permit the pawl to engage with the said ratchet wheel. The pawl or dog 61 is then disengaged from the ratchet wheel 60 and the brakeman having hold of the hand lever may permit and control the rotation of the brake staff in a direction to release the brake until such rotation is stopped by means of the engagement of the stop lug 7 on the housing with the stop lug 6 upon the bearing. This operation may then be repeated as often as may be necessary to gradually release the brake, or all of the brake power may be released at once without dropping down the handle.

It should be understood that any other suitable form and construction of clutch mechanism than that illustrated may be employed for connecting the hand lever to the brake staff to rotate the same for applying the brakes and for disconnecting the said clutch mechanism when the said staff rotates in the opposite direction to release the brakes.

In one aspect my invention comprehends broadly the combination in a brake actuating mechanism of a drop lever with means independent of the said lever and operable by the brakeman or other person for the purpose of disengaging the clutch mechanism which is interposed between such drop lever and the brake staff. Such clutch mechanism may be of the construction illustrated by me in my drawings or may be of any other construction in which a ratchet device is secured to the brake staff and is adapted to be engaged by means whereby the brake applying lever or handle may be operatively connected to the said staff.

Having thus described my invention, I claim:—

1. Brake actuating mechanism including in combination a brake staff, a drop lever adapted to fold down out of the way, clutch mechanism interposed between said lever and said staff, and a pivoted member unaf-

fected by the movements of said lever for 65 rendering said clutch mechanism inoperative when desired.

2. Brake actuating mechanism including in combination a brake staff, a drop lever adapted to fold out of the way, clutch mechanism interposed between said lever and said 70 brake staff for operatively connecting said lever with said staff, and manually operable means unaffected by the movements of said lever for rendering said clutch mechanism 75 inoperative when desired.

3. Brake actuating mechanism including in combination a brake staff, a ratchet thereon, a drop lever adapted to fold down out of the way, a pawl interposed between said lever and said staff and manually operable means movable independently of said lever for withdrawing said pawl from engagement with its ratchet when desired.

4. Brake actuating mechanism including 85 in combination a brake staff, ratchet mechanism for said staff, a drop handle adapted to fold down close to said staff and pivotally mounted means manually operable to disconnect the ratchet mechanism when desired. 90

5. Brake actuating mechanism including in combination a brake staff, a ratchet fastened to said staff, a housing inclosing said ratchet, a pawl carried by said housing, a drop handle pivoted to said housing and 95 manually operable means pivoted to said housing for withdrawing said pawl when desired.

6. Brake actuating mechanism including 100 in combination a brake staff, a ratchet fastened to said staff, a housing adapted to swing about said ratchet, a pawl carried by said housing and adapted to engage said ratchet, a drop handle pivoted to said housing and manually operable means pivoted to 105 said housing and having an extension engaging said pawl whereby the pawl may be withdrawn from operative engagement with its ratchet when desired.

7. Brake actuating mechanism including 110 in combination a brake staff, a drop lever, clutch mechanism interposed between the said drop lever and the said brake staff whereby the said drop lever when rotated in one direction angularly about the axis of the staff causes corresponding rotation thereof, and manually operable means supported 115 near said staff and independently of the said lever for disengaging the said clutch mechanism, whereby the said lever is operatively disconnected from the said brake staff and may be rotated thereon independently thereof.

8. Brake actuating mechanism including 125 in combination the brake staff, a ratchet device secured to the said staff, means movable independently of the said ratchet device and adapted for engagement therewith, a drop

lever having means for causing the movement of the said movable means from and into engagement with the said ratchet device as the said lever is dropped and raised, and 5 manually operable means independent of the said lever for causing disengagement of the said movable means from the said ratchet device, whereby the said drop lever may be disconnected from the said brake staff at the 10 will of the brakeman or other person.

9. Brake actuating mechanism including in combination a brake staff, means for rotatably supporting the said staff, a ratchet device secured at the upper end of the said staff, a housing secured upon the said brake staff and surrounding the said ratchet device, the said ratchet device and the said housing being relatively movable, a clutch device movably supported upon the said 15 housing, a drop lever having pivotal connection with the said housing and having means for engagement with the said clutch device to disengage the same from the said ratchet device when said lever is in dropped position, 20 means for causing the said clutch device to engage the said ratchet device when the said lever is in horizontal position, and manually operable means independent of the said lever for disengaging the said clutch device 25 from the said ratchet device for the purpose stated.

10. Brake actuating mechanism including in combination a brake staff, means for rotatably supporting the said staff, a ratchet 30 wheel secured upon the said brake staff, a housing having rotatable connection with the said staff, a pawl supported upon the said housing and adapted to be engaged with and to be disengaged from the said ratchet 35 wheel, a hand lever having pivotal connection with the said housing and having means associated therewith for causing movement of the said pawl to disengage the same from the said ratchet wheel when the said lever is 40 moved into position substantially parallel with the said brake staff, means for causing movement of the said pawl to engage the said ratchet wheel when the said lever is moved on its pivot into horizontal position, 45 and means supported upon the said housing and being under control of the brakeman or other person for causing disengagement of the said pawl from the said ratchet wheel independent of the said lever for the purpose 50 stated.

11. Brake actuating mechanism, including in combination a brake staff, a drop lever, 55 clutch mechanism for operatively connecting the said lever with the said brake staff 60 whereby rotation of the latter may be caused to effect the application of the brake, stop devices for limiting the rotative movement of the said brake staff when the said clutch mechanism is in position to operatively connect the drop lever to said staff, and manu-

ally operable means independent of the said lever for actuating a member of the said clutch mechanism to disengage the same from another member thereof whereby the said brake staff may rotate independently of 70 the said lever.

12. Brake actuating mechanism including in combination a brake staff, a ratchet wheel secured at the upper end of the said brake staff, a housing secured to said brake staff 75 and surrounding the said ratchet wheel, a pawl supported upon the said housing and adapted to be engaged with and disengaged from the said ratchet wheel, a lever having pivotal connection with the said housing 80 and the said lever having means beyond its pivot for engagement with the said pawl to retract and disengage the same from the said ratchet wheel when said lever is dropped into vertical position, means for causing 85 movement of the said pawl into engagement with the said ratchet wheel when the lever is in horizontal position, and means supported upon the said housing for disengaging the said pawl from the said ratchet 90 wheel at the will of the brakeman or other person.

13. Brake actuating mechanism including in combination a brake staff, ratchet mechanism supported at the upper end of the said 95 brake staff, a drop lever operatively related to the said ratchet mechanism and having means whereby when in a vertical position one member of the said ratchet mechanism is held out of engagement with the other 100 member thereof, means for causing engagement of the members of the said ratchet mechanism when the said lever is in horizontal position, and a manually operable lever supported independently of the said 105 drop lever for disengaging one of the members of the said ratchet mechanism from the other when the said drop lever is in horizontal position for the purpose stated.

14. Brake actuating mechanism including 110 in combination a brake staff, means for rotatably supporting the said brake staff, a ratchet wheel secured upon the said brake staff at its upper end, a housing secured upon the said brake staff and surrounding 115 the said ratchet wheel and having an opening therein, a pawl supported in said opening and adapted to cooperate with the said ratchet wheel, a drop lever having pivotal connection with the said housing, said drop 120 lever being provided with means for retracting the said pawl when it is moved into vertical position, a spring pressed plunger supported upon the said drop lever and operating to move the 125 said pawl into engagement with the said ratchet wheel when the said lever is in horizontal position, and manually operable means also having connection with the said housing for retracting the said pawls to dis- 130

engage the same from the said ratchet wheel for the purpose stated when the said lever is in horizontal position.

15. Brake actuating mechanism including in combination a brake staff, means for rotatably supporting the said staff, a ratchet wheel secured to the said brake staff at its upper end, a housing surrounding the said ratchet wheel and also secured to the said 10 brake staff, the said housing having a lateral projection and an opening through one side in alinement with the said projection, a pawl slidably supported in the said opening and adapted to be engaged with and disengaged 15 from the said ratchet wheel, a drop lever pivoted to the said lateral projection and having means beyond its pivot for engagement with the said pawl to retract the same when the lever is in vertical position, and a 20 spring pressed plunger supported upon the said drop lever and adapted to engage with the outer end of the said pawl to cause movement of the latter into engagement with the said ratchet wheel when the said lever is in 25 horizontal position.

16. Brake actuating mechanism including in combination a brake staff, means for rotatably supporting the said staff, a ratchet wheel secured to the said brake staff at its 30 upper end, a housing surrounding the said ratchet wheel and also secured to the said brake staff, the said housing having a lateral projection and an opening through one side in alinement with the said projection, 35 a pawl slidably supported in the said opening and adapted to be engaged with and disengaged from the said ratchet wheel, a drop lever pivoted to the said lateral projection and having means beyond its pivot for engagement with the said pawl to retract the same when the lever is in vertical position, a spring pressed plunger supported upon the 40 said drop lever and adapted to engage with the outer end of the said pawl to cause movement of the latter into engagement with the said ratchet wheel when the said lever is in horizontal position, and manually operable means pivotally supported upon the said lateral projection and being 45 independent of the said handle for effecting the retraction of the said pawl to disengage the same from the said ratchet wheel at the will of the brakeman or other person.

17. Brake actuating mechanism including 55 in combination a brake staff, means for rotatably supporting the said brake staff, a ratchet wheel secured upon the said brake staff at its upper end, a housing surrounding the said ratchet wheel and having a projection extending laterally therefrom, a pawl for engaging the said ratchet wheel which pawl is slidably supported upon the 60 said housing and projects into the said laterally extending projection and the said pawl being provided with a vertical slot, a

drop lever pivoted to the said lateral projection and having means for engagement with the said pawl to retract the same when said lever is in vertical position, and a spring 70 pressed plunger supported upon the said lever and adapted to engage with the outer end of the said pawl to cause inward movement thereof to engage the said ratchet wheel when the said lever is in horizontal position, and a manually operable lever pivoted upon the said lateral projection, the said lever having an extension which extends through the upper side of the said lateral projection into engagement with the said pawl at one end of the said slot, the 75 said lever being adapted to be moved in one direction to disengage the said pawl from the said ratchet wheel when the said drop lever is in horizontal position.

18. In hand operated brake actuating 85 mechanism, a rotatable brake staff, clutch mechanism adapted to convert oscillatory movements into uni-directional rotary movements of the brake staff, a housing member for the entire clutch mechanism, a hand lever pivoted to the housing member so that it can be swung from a non-interfering depending position to an extended operative position for oscillation thereof, the hand lever being provided with means beyond its 90 pivot for disengaging the clutch mechanism when in its depending position and for allowing engagement of the clutch mechanism when in its extended position and additional means for disengaging said clutch mechanism when said handle is extended; substantially as described.

19. In hand operated brake actuating mechanism, a rotatable brake staff, a ratchet fastened on the brake staff, a sliding pawl 105 adapted to engage the ratchet in one direction of oscillation and to disengage therefrom in the reverse direction of oscillation in order to convert oscillatory movements into uni-directional rotary movements of the brake staff, a member carrying the pawl, and a hand lever pivoted to said member so that it can be swung from a non-interfering depending position to an extended operative position for oscillating the pawl, the hand lever being provided with means beyond its 110 pivot for disengaging the pawl from the ratchet when in its depending position and for allowing the pawl to engage the ratchet 115 when in its extended position; substantially as described.

20. Brake actuating mechanism including in combination a brake staff, a ratchet wheel secured upon said brake staff, a housing having rotatable connection with said staff, a 125 sliding pawl carried by said housing and adapted to engage with and to be disengaged from the said ratchet wheel, a hand lever pivotally connected with said housing and having means associated therewith for 130

5 withdrawing said pawl away from said shaft when said lever is folded down into a position substantially parallel with the brake staff, and means for causing movement of 5 said pawl into engagement with its ratchet when said lever is moved outward into operative position.

10 21. Brake actuating mechanism including in combination a brake staff, a ratchet wheel secured upon said brake staff at its upper end, a housing secured upon said brake staff and surrounding the said ratchet wheel, a sliding clutch member supported in said housing and adapted to co- 15 operate with said ratchet wheel, a drop lever having pivotal connection with said housing, said lever being provided with a pair of lugs for slidably retracting said sliding clutch member when the lever is folded down out of the way, and a spring 20 operative to move said sliding clutch member into engagement with said ratchet wheel when said lever is in extended position.

25 22. The combination of a brake staff, a ratchet thereon, a housing inclosing said ratchet and adapted to swing about said staff, a sliding clutch member engaging said ratchet to turn said staff, a drop handle pivoted to said housing and adapted to fold down out of the way, a spring arranged to hold said clutch member in yielding engagement with said ratchet, and a drop handle having a bifurcated end carrying 30 lugs for engagement with said clutch member and serving automatically to slidably withdraw said clutch member from engagement with the ratchet when said handle drops to folded position.

35 23. In hand operated brake actuating mechanism, a rotatable brake staff, a ratchet fastened on the brake staff, a sliding clutch member adapted to engage the ratchet in one direction of oscillation and to 40 disengage therefrom in the reverse direction of oscillation in order to convert oscillatory movements into uni-directional rotary movements of the brake staff, a housing carrying said clutch member and a

hand lever pivoted to said housing so that 50 it can be swung from a non-interfering depending position to an extended operative position for oscillating the clutch member, the hand lever being bifurcated and provided with opposing lugs for disengaging 55 the clutch member from the ratchet when in its depending position and for allowing the clutch member to engage the ratchet when in its extended position.

60 24. Brake actuating mechanism including in combination a brake staff, a ratchet fastened to said staff, a housing inclosing said ratchet and adapted to swing about the same, a spring pressed pawl mounted to slide in said housing toward and away 65 from said shaft, an operating handle connected with said housing to swing the same and a releasing lever pivoted to the top of said housing and having one end projecting toward said shaft in convenient position 70 for depression, and having its other end projecting down into said housing and engaging with said sliding pawl to retract the same when desired; substantially as described. 75

80 25. Brake actuating mechanism including in combination a brake staff, a ratchet fastened to said staff, a housing inclosing said ratchet and adapted to swing about the same, a spring pressed pawl mounted to slide in said housing toward and away from said shaft, a drop handle pivoted to said housing and having a part adapted to engage said sliding pawl to withdraw the same when the handle drops and a releasing lever pivoted to said housing and having one end projecting thereover in convenient position for depression and having its other end engaging said sliding pawl to retract the same when desired; substantially as described. 85 90

In testimony that I claim the foregoing as my invention, I have hereunto signed my name this 12th day of June, A. D. 1912.

CHARLES A. LINDSTRÖM.

In the presence of—

FRANK E. MILLER,
JOHN A. TEUFER, Jr.
